Primary Examiner — Steven J Czyz

(57) **CLAIM**

The ornamental design for a makeup bag attachment, as shown and described.

DESCRIPTION

FIG. 1 is a front perspective view of a makeup bag attachment, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is its usage status diagram.

The broken lines in the drawings illustrate the portions of the makeup bag attachment, which form no part of the claimed design.

The dash-dot-dot-dash lines representing stitching are part of the claimed design.
